CLAIM

The ornamental design for apparatus for depositing cell samples on microscopic slide, as shown and described.

DESCRIPTION

FIG. 1 is a front perspective view from a left side of an apparatus for depositing cell samples on microscopic slide showing our design,

FIG. 2 is a front elevational view of the apparatus for depositing cell samples on microscopic slide shown in FIG. 1,

FIG. 3 is a right side view thereof,

FIG. 4 is a left side view thereof,

FIG. 5 is a top plan view thereof,

FIG. 6 is a bottom plan thereof; and,

FIG. 7 is a rear elevation view thereof.
